UNITED STATES PATENT OFFICE

2,550,341

PROCESS FOR CONTROLLING THE CONCENTRATIONS OF SUSPENSIONS

Freerk J. Fontein, Heerlen, Netherlands, assignor to De Directie van de Staatsmijnen in Limburg, Heerlen, Netherlands

Application August 14, 1946, Serial No. 690,550
In the Netherlands August 28, 1945

1 Claim. (Cl. 209—211)

1

This invention relates to process and apparatus for the separation of a suspension into two fractions of controllable concentration, using a cyclone.

It has heretofore been known to control the concentration of the fractions separated by a cyclone by a suitable choice of diameters of the outlet openings of the cyclone. However, these cyclones are ordinarily relatively small and the apex opening through which the heavier fraction is discharged may have a normal diameter as small as or smaller than $\frac{3}{4}$ of an inch. Consequently there is the constant danger of clogging or unduly narrowing the apex opening. In the case of a cyclone used to thicken separating suspensions such as are used in the sink-float type of washing boxes, such a clogging or narrowing immediately affects the separating action since the lighter fraction will immediately increase in concentration with the resultant loss of solid constituents from the apex discharge.

It is the object of the present invention to overcome this difficulty. In accordance with the invention, the apex discharge is immediately received in a suspension body which has an adjustable resistance to the entering suspension, the resistance being adjusted, for example, by withdrawal from the body at a certain rate. In terms of apparatus, a closed receiver is associated with the apex opening of the cyclone, the receiver being filled with suspension and having a controllable outlet. If the capacity of the receiver outlet is increased, the pressure in the receiver decreases and the concentration of the suspension leaving the cyclone at its apex also decreases. This results, with some retardation, in the decrease of the concentration of the suspension discharging from the receiver outlet so that the specific gravity of discharge of the whole installation decreases. On the other hand, if the capacity of the receiver outlet is diminished, then pressure in the receiver increases and the concentration of the suspension leaving the cyclone at its apex increases, with the result, with some retardation, of the increase of concentration of the suspension discharging from the receiver so that the specific gravity of discharge of the whole installation increases. The advantages arising from the practice of the invention are especially notable when a number of cyclones are associated with a common receiver.

Apparatus suitable for the practice of the invention is shown by way of example in the accompanying drawing in which

Figure 1 is an axial section of an installation

2 comprising two cyclones associated with a common receiver and

Figure 2 is a fragmentary axial section of a receiver with another form of discharge control means.

Referring to Figure 1, reference numeral 5 designates a cyclone comprising a shallow cylindrical top portion 6 having an inlet opening 7 at the end of a tangentially directed feed pipe 8. A cover plate 9 is secured to the top of portion 6 and has a central discharge opening 10. Reference numeral 11 designates a conical portion depending from portion 6 coaxially therewith and having an apex opening 12 aligned with the base opening 10. As here shown, the lower end of portion 11 is flanged at 13 and is secured to the top wall 14 of a closed receiver or tank 15 which has an opening 16 registering with the apex opening 12. The receiver has a conical body portion 17 which terminates downwardly in a housing 18 for a star wheel 19 adapted to be driven at a controllable speed for controlling the rate of discharge from the receiver.

Reference numeral 20 designates a cyclone like cyclone 5 and similarly associated with the receiver.

In the operation of the apparatus, the liquid suspension to be thickened is fed to the cyclones through the feed pipes 8. The infed suspension will move in inner and outer vortices having the same rotational sense. However, the inner vortex moves axially toward the base discharge opening 10 while the outer vortex moves axially toward apex opening 12. The fraction of higher concentration leaves the outer vortex of each cyclone through the apex opening 12 and the fraction of lower concentration leaves the inner vortex of each cyclone through the base opening 10. When the receiver is filled by the apex discharges, the star wheel is rotated at a speed to maintain the desired pressure in the receiver and, hence, the desired resistance to the entry of the apex discharges. It will be observed that receiver 15 thus defines a pressure zone.

The advantage of providing a plurality of small cyclones instead of a single large one is that the precipitation efficiency of the small cyclone is greater, and this efficiency does not decrease as much as that of the larger cyclone when the specific gravity of the apex discharge increases. Hitherto the lower limit of the cyclone size has been determined principally by the size of the apex aperture which decreases in proportion to the size of the cyclone. However, if several

55 small cyclones discharge into a single suspension-

filled receiver, the specific gravity of the discharge is no longer determined by the size of the apex of the cyclone but by the pressure in the receiver and, consequently, the size of the apex openings can be large enough so as to eliminate the danger of clogging.

The average capacity of the receiver outlet is, of course, independent of the number of cyclones and only dependent upon the capacity of the installation, and this average outlet capacity will be the same in the case of a single large cyclone or a number of small cyclones discharging into the receiver. Furthermore, it is obviously much simpler to control the outlet capacity of a single container than to control the apex capacity of a number of small cyclones.

The following is given as an example of performance:

The thickening of 550° gallons per hour of a loess suspension from a sink-float coal washing plant from an average specific gravity of 1.06 to an average specific gravity of 1.6 can be accomplished in a single cyclone having a top diameter of one foot, an inside feed pipe diameter of 2 inches, a base outlet diameter of 2 inches, and an apex outlet diameter of $\frac{3}{4}$ of an inch average. The loss of solid constituents in the suspension leaving through the base opening of the cyclone amounts to 50%, that is, about one ton per hour. Similarly thickening the same quantity of suspension in six cyclones discharging into a common receiver filled with suspension up to the same specific gravity, the maximum diameter of the cyclones is $2\frac{1}{8}$ inches, inlet diameter $\frac{3}{4}$ inch, diameter base outlet $\frac{3}{4}$ inch, and diameter of the apex outlet $\frac{3}{4}$ inch. The capacity of the receiver outlet is equivalent to a diameter of $1\frac{1}{8}$ inches, and the loss of solid constituents through the base outlets of the cyclones amounts to 25% or .5 ton per hour.

The receiver discharge can be controlled in any suitable manner. For example, instead of the rotary star wheel of Figure 1, I may use a valve 21, Figure 2, secured to the lower end of the receiver 17, the valve preferably being designed to permit as smooth a flow as possible.

Other variations in the form and arrangement of parts are possible and are contemplated as under the invention as defined in the following claim.

I claim:

A method of thickening a suspension of solids

in a liquid into fractions so that the desired fraction will be thickened to have a predetermined concentration value, comprising simultaneously feeding the suspension tangentially to the base area of a plurality of conical spaces and compelling it to move in each of said spaces in inner and outer vortices having the same rotational sense but of opposite axial directions, continuously withdrawing a part of the suspension from the inner vortices and discharging it axially from the center of the base end of each conical space to thereby obtain a fraction from each space having a relatively low concentration value, continuously withdrawing a part of the suspension from the outer vortex at the apex of each conical space to thereby obtain a desired fraction having a relatively high concentration value and discharging the last-mentioned fraction from the apices of the conical spaces directly into a larger confined pressure zone surrounding the apex discharges of the conical spaces and filled with the desired fraction, withdrawing the last-mentioned fraction from a portion of the pressure zone remote from the apex discharges of the conical spaces and controlling the pressure in the pressure zone by controlling the rate of withdrawal of the desired fraction from the pressure zone to thereby obtain the desired concentration of solids in the discharge from the apices of the conical spaces.

FREERK J. FONTEIN.
